UNITED STATES PATENT OFFICE.

NICALO MICUCCI, OF PHILADELPHIA, PENNSYLVANIA.

REWINDING MECHANISM FOR TALKING-MACHINES.

1,398,879.

Specification of Letters Patent. Patented Nov. 29, 1921.

Application filed June 16, 1919. Serial No. 304,525.

To all whom it may concern:

Be it known that I, NICALO MICUCCI, a subject of the King of Italy, residing at Philadelphia, in the county of Philadelphia and State of Pennsylvania, have invented new and useful Improvements in Rewinding Mechanism for Talking-Machines, of which the following is a specification.

This invention relates to talking machines and it has for its main object to provide a talking machine the motive mechanism whereof, is pedal operated, that is to say, the driving mechanism can be wound up by foot power.

A further object of my invention is to provide means whereby the motive mechanism is prevented from being accidentally overwound.

The invention also includes other novel objects and features of construction and arrangement hereinafter more definitely specified.

With the above objects in view, the nature of which will more fully appear as the description proceeds, the invention consists essentially in the novel construction, combination and arrangement of parts as herein fully described, illustrated, and particularly pointed out by the appended claim.

In the further disclosure of the invention, reference is to be had to the accompanying sheets of explanatory drawings, constituting a part of this specification, in which similar characters of reference denote corresponding parts in all the views; and in which,—

Figure 1 is a front elevation of a talking machine embodying my improvements.

Fig. 2 is a side elevation of the same with parts broken away or in section to show the underlying structure.

Fig. 3 is an enlarged detail sectional elevation of the pedal mechanism.

Fig. 4 is a front elevation to an enlarged scale of the motor for operating the machine; and

Fig. 5 is a side elevation of the same looking to the left hand of Fig. 1.

Fig. 6 is a detail section showing the slippage clutch.

Figs. 7 and 8 are detail views of the roller clutches.

Referring more particularly to the views, the numeral 10, designates a talking machine cabinet which comprises an upper part

11, in which is located the motive mechanism, an intermediate or storage section 12, for the reception of the records, and a lower part 13, in which is located the pedal mechanism designated generally by the numeral 14, the entire cabinet being mounted on ball casters 15, whereby said cabinet can be easily moved about from place to place.

Referring more particularly to Figs. 4, 5, the motive mechanism comprises a spring winding drum 16, having a gear 17, meshing with a pinion 18, mounted on a shaft 19, said shaft carrying a second gear 20 in gear with a pinion 21 carried by a shaft 22. This shaft 22 has secured thereto a toothed wheel 23, in gear with the governor mechanism 24, and it is to be noted that all of the foregoing parts are constructed and arranged in accordance with the well known methods of arranging a spring motor.

In accordance with my invention I mount a shaft 25, adjacent the above described mechanism and key or otherwise secure thereon a gear-wheel 26, in mesh with a pinion 27, mounted on a shaft 29, that carries the record supporting platform and I wish to here point out that the shaft 29, is mounted in a removable bearing 31.

Supported by a depending bracket or framework 32, beneath the mechanism above described, is a vertical shaft comprising upper and lower parts 33, 34, respectively, said parts being connected axially in line with one another by a slippage clutch 35, and the upper part 33, has associated therewith a roller clutch 36 for preventing back motion. Keyed or otherwise connected to the lower part 34, is a bevel wheel 37, in gear with a bevel wheel 38, on a horizontal shaft 39, mounted in bearings 40, 40, integral with the framework 32. This shaft 39 has mounted thereon, roller clutches 41, 41, to which are attached crank members or levers 42, to the free ends whereof are connected the ends of cords or cables 43, which pass over pulleys 44, mounted in the cabinet 10, as and where necessary, and the lower ends of said cords or cables 43, are connected to eye-pieces 45, attached beneath the pedals 46, which are hinged at 47, to brackets 48, carried by tubular elements 49, slidably mounted on rods 50,

supported by C-springs 51, attached rigidly to the bottom 52 of the cabinet 10. Thus it will be readily seen that the pedals 46,

can be drawn outwardly from the lower section of the cabinet or retracted thereinto as desired.

The slippage clutch 35 includes clutch members 59 and 60, one of said members being secured to the adjacent ends of the upper and lower parts 33 and 34 of the vertical shaft. The member 59 carries a band 61 which encircles the member 60, being adjustably secured to the member 59 as indicated at 62. The band 61 may thus be tensioned so as to bind upon the member 60 and in the ordinary operation of rewinding, will cause the upper and lower parts 33 and 15 34 of the vertical shaft to rotate together. The band 61 is so tensioned however, that when the spring motor has become sufficiently wound the said upper and lower parts 33 and 34 of the vertical shaft will be 20 capable of relative movement and damage to the spring motor will thus be prevented. The roller clutch 36 comprises members 62 and 63, the former being provided with a cam clutch 64 within which a roller 65 operates. The action of this roller will grip and cause the members 62 and 63 to rotate in unison when the shaft revolves in one direction, but will permit of independent movement between the members 62 and 63 25 when the shaft is rotated in an opposite direction. The roller clutches 41 are similar in construction to the roller clutch 36 just described, except, that they may be provided with a plurality of cam notches 66 within 30 which operate the rollers 67. The action of the clutches 44 is to grip the shaft 39 when the pedals are operated to cause the levers 42 to move in one direction, but to release

said shaft when the lever is moved in an opposite direction. This causes the shaft 39 40 to be revolved in one direction only.

In order to provide a simple means for controlling the speed of the machine I extend the governor shaft 53, somewhat and mount thereon a lever 54, which is connected by a link 55, to a handle or indicator element 56 adapted to pass over an appropriate indicator 57 mounted on the front of the machine.

From the foregoing it will be readily 50 seen that by my invention I provide an extremely simple and effective pedal operated mechanism for winding-up or rewinding the motor of a talking machine, and I wish it clearly understood that I do not limit 55 myself to the precise details hereinbefore set forth, as other combinations and arrangements of the several parts will be self-evident without in any way departing from the spirit of the invention, the scope where- 60 of is defined in the appended claim.

Having described my invention, I claim,—

The combination with a talking machine having a spring motor, of a rewinding mechanism comprising a compound shaft 65 including axially aligned sections, a slippage clutch connecting said sections, a second shaft disposed at right angles to the first mentioned shaft and geared thereto, spaced roller clutches carried by said second shaft, 70 cranks connected to said clutches, operating pedals and flexible connections between the pedals and cranks.

In testimony whereof I affix my signature.

NICALO MICUCCI.
